UNITED STATES PATENT OFFICE.

WILLIAM G. KENDALL, OF NEWARK, NEW JERSEY.

VANITY CASE.

Application filed July 29, 1926. Serial No. 125,632.

My invention relates to a new and improved vanity case or compact holder.

One of the objects of my invention is to provide a new and improved vanity case which shall be adapted to contain two removable cosmetic compacts, each of which shall be readily and separately accessible and removable.

Another object of my invention is to provide a device of this character which shall be simple and efficient and economical to manufacture.

Another object of my invention is to provide a device which shall be compact and which will have an ornamental appearance.

Other objects of my invention will be set forth in the following description and drawings which illustrate a preferred embodiment of my invention, it being understood that the above general statement of the objects of my invention is intended merely to generally explain the same and not to limit it in any manner.

Fig. 1 is a perspective view showing the cover of the vanity case in the vertical position and showing the lower compartment or drawer partially withdrawn.

Fig. 2 is a sectional view taken on the line 2—2 of Fig. 3.

Fig. 3 is a sectional view taken on the line 3—3 of Fig. 2.

Fig. 4 is a sectional view taken on the line 4—4 of Fig. 3.

Fig. 5 is a side elevation showing the cover in its rearward position, the lower compartment or drawer in the outer position, and the upper tray or compartment separated from the casing of the device.

Fig. 6 is a top view of the device shown in Fig. 5.

Fig. 7 is a vertical sectional view of the device in the position shown in Fig. 6.

Fig. 8 is a bottom plan view of the top compartment or drawer.

Fig. 9 is a perspective view of the guide for the bottom sliding drawer.

The vanity case is provided with a body portion 10 having a cover 13 connected thereto by means of a hinge 15. The cover 13 is provided with a mirror 27 and it has a latch or detent 24 of the usual construction whereby the cover can be held in the closed position.

As shown more clearly in Figs. 7 and 9, the casing 10 is provided with a guide for the lower drawer or compartment 12. This

guide comprises a metal member 32 bent into a U-shape as shown in Fig. 9. The legs of the member 32 are provided with longitudinal guide recesses or slots 29 and with lateral slots 28 which are separated from the longitudinal guide slots 29 by mean of suitable webs, as shown in Fig. 9.

The bottom sliding drawer or compartment 12 is provided with pins 30 which are adapted to slide in the guide grooves 29 of the guide 32. The front of the casing 10 is provided with an aperture 14 whose height is substantially the same as the height of the lower compartment 12. However, the height of the opening 14 is made sufficiently great to enable the lower compartment 12 to be slightly tilted with respect to the casing 10. Hence, the guide 32 and the lower compartment 12 can be assembled without the casing 10 by fitting the lugs or pins 30 within the slots 29 and the front of the compartment 12 can then be moved through the opening 14. At the same time, the guide 32 can be moved forwardly until it fits in proper position within the casing 10. The front of the lower compartment 12 is provided with a finger-hold 22.

However, the guide 32 could be permanently affixed to or be otherwise formed in the casing 10, as my invention is not limited in this respect to the particular construction shown in this preferred embodiment.

However, this construction permits the parts to be simply and economically manufactured and assembled.

The top compartment 11 is provided with a cylindrical seat for receiving a compact 17, and the bottom compartment 12 is provided with a similar seat for receiving a second compact 16. These compacts are preferably formed in metal bases or holders as shown in my previously issued U. S. Patent No. 1,194,185, and the bottom compartment 12 is provided with holding tongues 19 and the upper compartment 11 is provided with similar holding tongues 18, for engaging these compacts while permitting the ready removal thereof.

The upper compartment 11 is provided with a blade spring 20 which tends to upwardly force the base of the upper compact 17 when the said spring 20 is bent so as to curve it upwardly. The outer end of the spring 20 is associated with a push member 21 which can be pushed inwardly by the user. A blade spring 31 is provided upon

the underside of the upper compartment 11 and this provides the necessary resilience for forcing the member 21 to the outer position.

5 As shown clearly in Fig. 7, for example, the member 21 is provided with a vertical part 23 which moves in a guide slot in the upper face of the upper compartment 11 so as to positively guide the movement of the 10 said member 21. As clearly shown in Fig. 7, the outer end of the spring 20 is curved to provide a doubled end 20^a and this is actuated by the member 21. As shown in Fig. 2, for example, the pusher 21 projects 15 through a slot in the upper portion of the front face of the casing 10 so that it can be readily manipulated.

The casing 10 is provided at the four corners thereof with indentations 25^a so that 20 four small lugs are formed upon the inner face of the said casing 10 and these lugs are adapted to engage corresponding depressions 25 in the upper compartment 11 in order to firmly retain the same. The cover 13 is provided with a frame 26 for the mirror 27.

As shown in Fig. 6, the bottom compartment 12 is provided with a small hole in the bottom thereof by means of which the bottom compact 16 can be removed. As shown 30 in Fig. 4, for example, the respective compacts are provided with individual powder puffs. One of these compacts may be a face powder compact and the other may be a rouge compact.

35 It is obvious that when the cover of the vanity case is opened that the top compact is immediately accessible and that the bottom compact can be made readily accessible by sliding the bottom drawer outwardly.

40 As shown in Fig. 2, the pins 30 can slide to the rear of the guide 32 and the webs separating the vertical slots 28 from the lateral slots 29 are given a suitable concave shape in order to permit this. Hence, in assembling 45 the guide 32 and the lower compartment 12, they can be first moved into the relative position shown in Fig. 2 and the parts thus assembled can be properly located in the casing 10.

50 All the parts of the device are preferably made of suitable stamped metal.

Thus, although I have shown the guide means 32 as being formed separately from the casing in my preferred embodiment, I 55 do not limit my invention to such independent or separate construction of the guide means 32. Heretofore, in guiding sliding drawers in compact boxes of this character, it has been customary to form the bottom of 60 the box with a guide slot or the like and this was unsightly and frequently clogged. I believe and claim that I am the first to provide suitable guide means in the vertical walls of a compact holder as before specified.

65 It would be within the scope of my invention to replace the slots 29 by corresponding grooves or depressions in the longitudinal walls of member 32, or by depressions in the vertical walls of the casing.

I have shown a preferred embodiment of 70 my invention but it is clear that numerous changes and omissions could be made without departing from its spirit.

I claim:

1. A vanity case comprising a rectangular 75 casing having an opening in a wall thereof, a slideable tray adapted to be longitudinally slid to and fro through the said opening, a guide associated with said opening and consisting solely of a U-shaped metal strip independent of said tray and located within the said casing, the base of the said U-shaped metal member being opposite the opening in the said casing and being adjacent a vertical wall of the said casing, the said guide contacting with the rear wall and with the longitudinal walls of said casing, the legs of the said U-shaped guide member having longitudinal guide grooves formed therein, the rear portion of the said tray having lugs 80 adapted to engage the guide grooves in said legs, the height of the said opening being sufficient to permit the rearward insertion of the said sliding tray.

2. A vanity case comprising a rectangular 85 casing having an opening in a wall thereof, a slideable tray adapted to be longitudinally slid to and fro through the said opening, a guide associated with said opening and consisting solely of a U-shaped metal strip independent of said tray and located within the said casing and the base of the said U-shaped metal member being opposite the opening in the said casing and being adjacent a vertical wall of the said casing, the said guide contacting with the rear wall and with the longitudinal walls of said casing, the legs of the said U-shaped guide member having longitudinal guide grooves formed therein, the rear portion of the said tray 90 having lugs adapted to engage the guide grooves in said legs, the height of the said opening being sufficient to permit the rearward insertion of the said sliding tray, the outer ends of the said guide grooves being 95 spaced from the outer ends of the said legs.

3. A vanity case comprising a rectangular 100 casing having an opening in a wall thereof, a slideable tray adapted to be longitudinally slid to and fro through the said opening, a guide associated with said opening and consisting solely of a U-shaped metal strip independent of said tray and located within the said casing and the base of the said U-shaped metal member being opposite the 105 opening in the said casing and being adjacent a vertical wall of the said casing, the said guide contacting with the rear wall and with the longitudinal walls of said casing, the legs of the said U-shaped guide member 110 having longitudinal guide grooves formed therein, the rear portion of the said tray having lugs adapted to engage the guide grooves in said legs, the height of the said opening being sufficient to permit the rearward insertion of the said sliding tray, the outer ends of the said guide grooves being 115 spaced from the outer ends of the said legs.

120

125

130

having longitudinal guide grooves formed therein, the rear portion of the said tray having lugs adapted to engage the guide grooves in said legs, the height of the said opening being sufficient to permit the rearward insertion of the said sliding tray, the said guide grooves being U-shaped, one of

the branches of each said guide groove being substantially parallel to the bottom of the casing and the other branch being substantially perpendicular to said bottom of the casing. 10

In testimony whereof I affix my signature.
WILLIAM G. KENDALL.
